UNITED STATES PATENT OFFICE.

WILLIAM A. HAUCE, OF SPRINGFIELD, OHIO.

HAIR-CRIMPING TOOL.

SPECIFICATION forming part of Letters Patent No. 278,944, dated June 5, 1883.

Application filed March 20, 1883. (No model.)

To all whom it may concern:

Be it known that I, WILLIAM AUGUSTUS HAUCE, a citizen of the United States, residing at Springfield, in the county of Clarke and State of Ohio, have invented new and useful Improvements in Hand Crimping-Tools, of which the following is a specification.

My invention relates to hand crimping-tools in which the crimping-jaws are operated by handles pivoted like and operating like the handles of shears to open and close the crimping-jaws with one hand; but as hitherto manufactured the jaws have been made of corrugated sheet-iron or other metal, and have tended to seriously injure the hair by an excess of heat, and also required to be frequently heated.

The object of my improvement is to avoid this destructive injury to the hair by making the crimping-jaws of non-metallic heat absorbing and retaining material, and fastening the shear-handles thereto, as hereinafter specifically set forth.

In the accompanying drawings, Figure 1 represents a view in perspective of a hand crimping-tool embracing my invention, and Fig. 2 a sectional view of the crimping-tool on the line $x x$ of Fig. 1.

In the drawings, A A are the crimping-jaws, made of non-metallic heat absorbing and retaining material—such as that used in the manufacture of crockery—and fluted on the meeting faces, as shown.

B B are the handles, made of metal and similar in construction and in operation to the common shears; but the parts which would be cutting-blades in shears are here widened flattened clips D, having holes through which screws or rivets $a a a$ are driven to fasten them to the crimping-jaws, holes being made in the latter for that purpose. These handles, being flat and broad at their connections with the jaws, give a firm, strong, and rigid connection, thus insuring that the fluted surface of one crimping-jaw shall always fit that of the other in the process of crimping, as is well under-

stood. But the most important point of my invention is in the selection of the non-metallic heat absorbing and retaining material for the jaws. I prefer to make them of the same material as that used in the manufacture of crockery-ware, stoneware, fire-clay, or of wood. If of fire-clay, they may be heated by direct contact with fire or flame; but usually it is only necessary to hold the jaws above a gas-jet or lamp-chimney; or they may be brought to a most desirable temperature by plunging the jaws in boiling water.

It is a fact well known that the metallic crimpers, if not used with the utmost caution, are exceedingly injurious to the hair, and in some instances destructive. They also soon give off their heat and require frequent applications to fire and flame, and are liable to rust and roughening and general uncleanliness. My device is entirely free from these objections, is neat and cleanly, and is cheaply made; and by my construction of jaws they are made thick, so as to cause them to retain the heat longer, and yet they are of no greater cubic surface than those made of corrugated sheet metal.

Of course the tool may be used in laundry work, or wherever a crimper is used, if desired, as well as for the hair; but my main object was to produce a crimping-tool harmless to the human hair.

I claim—

A crimping-tool consisting of crimping-jaws made of non-metallic heat-absorbing material, fluted on their meeting faces, and operated by pivoted handles secured thereto, substantially as described, for the purpose specified.

In testimony whereof I have hereunto set my hand in the presence of two subscribing witnesses.

WILLIAM AUGUSTUS HAUCE.

Witnesses:

JAS. JOHNSON, Jr.,
GEO. S. DIAL.

It is hereby certified that the name of the patentee of Letters Patent No. 278,944, granted June 5, 1883, for an improvement in "Hair-Crimping Tools," was erroneously printed and written "William A. Hause" instead of *William A. Hance*; that it appears from affidavits filed in the Patent Office that the correct name is William A. Hance; and that this correction should be read in the said Letters Patent to make the same conform to the record of the case in the Patent Office.

Signed, countersigned, and sealed this 3d day of July, A. D. 1883.

[SEAL.]

M. L. JOSLYN,
Acting Secretary of the Interior.

Countersigned:

E. M. MARBLE,
Commissioner of Patents.
